UNITED STATES PATENT OFFICE.

PAUL REINWALD, OF SAN FRANCISCO, CALIFORNIA.

FIRE-ESCAPE.

1,370,045.

Specification of Letters Patent.

Patented Mar. 1, 1921.

Application filed March 16, 1920. Serial No. 366,230.

To all whom it may concern:

Be it known that I, PAUL REINWALD, a citizen of the United States, and a resident of the city and county of San Francisco and 5 State of California, have invented a certain new and useful Fire-Escape, of which the following is a specification.

The invention relates to flexible fire escapes which may be lowered quickly from 10 a window in the event of fire.

An object of the invention is to provide a flexible fire escape which is normally wound on a reel and which may be readily 15 unwound and lowered from a window in the event of fire.

Another object of the invention is to provide means for securing the upper end of the fire escape to the window casing so that it cannot become dislodged.

20 A further object of the invention is to provide an improved form of flexible ladder in which the steps remain horizontal.

The invention possesses other advantageous features, some of which, with the 25 foregoing, will be set forth in the following description, where I shall outline in full, that form of the invention which I have selected for illustration in the drawings accompanying and forming part of the present 30 specification.

In said drawings—

Figure 1 is an elevation of a window showing the fire escape of my invention depending therefrom.

15 Fig. 2 is a vertical section through a window showing the means for securing the device of my invention.

Fig. 3 is an under side view of one of the steps of the fire escape.

20 Fig. 4 is a detail of one corner of a step showing the method of attaching the suspending member thereto.

Fig. 5 is a perspective of the winding reel.

25 Figs. 6 and 7 are details of the clamp.

The fire escape of my invention is of the flexible ladder type, provided with rigid steps which are maintained in a horizontal position at all times. The escape is particularly designed to be thrown from a window of a building and offers a safe escape to the ground. The device comprises a cross bar or holding bar 2 of sufficient strength to support the loaded ladder. This bar is 5 of greater length than the width of the window, so that when the ladder is unwound

from the window, the cross bar will engage the building wall 3 on opposite sides of the window 4 and firmly support the ladder. Passing through the cross bar 2 are two 60 ropes 5, either metallic or fabric, which depend to the ground and to which the steps 6 are secured. Each rope is doubled on itself, so that four strands of rope depend and each rope is secured to the cross-bar 65 by a U-bolt 7 or other suitable device, so that there is no movement of the ropes longitudinally with respect to the cross-bar. By preventing relative movement of the ropes and securing the ropes to the steps, relative 70 movement of the steps is prevented and they remain horizontal. The ropes are spaced apart laterally such distance that they readily pass through the window.

Means are provided for securing the 75 cross-bar to the window ledge or sill 8, so that it may not become displaced. Pivoted to the cross-bar 2 is a link 9, which when not in use folds against the cross-bar and which when in use, overlies the window sill 80 8. The link 9 is square in cross section and slidably arranged thereon is a clamping head 12 which is adapted to engage the edge of the window sill, to clamp the link and the cross-bar in position. The clamping 85 head 12 comprises two members 13—14, pivoted together at the top by the links 15 and provided with square apertures in which the link 9 makes a snug sliding fit. By spreading the members 13—14 apart at the bottom, 90 they grip the link 9. The members are spread at the bottom by the eccentric cam 16 journaled in the member 13 and bearing against the face of the member 14, which cam is operated by the lever 17. In operation, the head is shoved tightly against the edge of the window sill and the lever 17 pulled up to clamp the cross-bar to the window frame.

The ropes 5 are provided at suitable intervals with steps 6, which are preferably made of wood. The steps are cut away at each corner forming seats through which the ropes pass. Below each step, each rope is engaged by a clamp 18, the wings 19 of which extend under the step in a longitudinal direction. The wings are provided with apertures through which the shouldered bolts 21 pass, the step resting on the bolts. The bolts are provided with nuts for clamping the wings 19 and extend beyond the edge of the step into the brackets 22 which

are secured to the step. This produces a strong construction in which all liability of slippage of the steps on the ropes is eliminated. The proper number of steps, spaced apart a proper distance, are provided to enable a person to reach the ground from the window from which the fire escape depends. A weight 23 is preferably attached to the lower step to insure the descent of the 10 ladder when it is thrown from the window.

The cross-bar or anchor bar 2 is provided at its ends with trunnions 24, and, when not in use, the cross-bar acts as a reel upon which the ladder is wound. The trunnions on the 15 cross-bar are inserted in bearings in the upper end of the standards 25 on the carriage 26, and an extension 27 on one trunnion is shaped to receive a crank 28, for rotating the cross-bar. The upper ends of the 20 standards are preferably provided with straps 29 to prevent unseating of the trunnions during rotation of the cross-bar. The carriage 26 is provided with casters 31, so that it may be readily moved into desired positions. In the event of fire, the carriage is 25 rolled to a window, the lower end of the ladder thrown therefrom and the remainder of the ladder unwinds from the carriage until the cross-bar disengages itself and contacts with the wall at the sides of the window. The cross-bar is then clamped in 30 position and the apparatus is ready for use.

I claim:

1. A fire escape comprising a rope ladder

adapted to depend from a window, a cross-bar to which the rope ladder is attached and which is adapted to engage the building wall at the side of the window and a clamp foldable on the cross-bar and adapted to engage the window sill to lock the cross-bar in position. 35

2. A fire escape comprising a rope ladder adapted to depend from a window, a cross-bar to which the rope ladder is attached and which is adapted to engage the building wall 40 at the side of the window, a link pivoted to the cross-bar and overlying the window sill and a head on the link adapted to engage the window sill to clamp the cross-bar in position. 45

3. A fire escape comprising a plurality of depending ropes, a plurality of rigid steps secured to said ropes, a clamp engaging each rope immediately below each step, bolts engaging said clamps and underlying the step 50 and brackets secured to the steps and engaging said bolts. 55

4. A fire escape comprising four depending ropes, a plurality of rigid steps secured to said ropes at the four corners of 60 each step, clamps secured to the ropes and underlying the corners of the steps, bolts securing the clamps together in pairs and brackets engaging the bolts and secured to the steps. 65

In testimony whereof, I have hereunto set my hand.

PAUL REINWALD
